CLAIM

The ornamental design for a shoe, as shown and described.

DESCRIPTION

FIG. 1 is a side view of a shoe showing our new design;

FIG. 2 is a rear perspective view thereof;

FIG. 3 is a rear view thereof;

FIG. 4 is an opposite side rear perspective view; and,

FIG. 5 is an opposite side view thereof.

The broken lines depicting the remainder of the shoe show features that form no part of the claimed design.
